(57) **CLAIM**

The ornamental design for a pedicure device, as shown and described.

DESCRIPTION

FIG. 1 is a front, top left perspective view of a second embodiment of a pedicure device showing my design; FIG. 2 is a front elevational view of the same; FIG. 3 is a rear elevational view of the same; FIG. 4 is a left elevational view of the same; FIG. 5 is a right elevational view of the same; FIG. 6 is a top view of the same; and, FIG. 7 is a bottom view of the same.

The broken lines depict portions of the pedicure device that form no part of the claimed design.

1 Claim, 4 Drawing Sheets
